WILLIAM V. PENNINGTON AND PAUL C. ISOM, OF LEBANON, KANSAS.

HOT-PLATE FOOT FEED.

Application filed October 29, 1926. Serial No. 145,047.

Our present invention has reference to a pedal means for operating the hot plate foot feed on the hot plate vaporizer now in general use upon the small class of automobile engines known as the Ford.

Our object is the provision of a means for this purpose which can be readily attached and which will not interfere with the free working of the hot plate feed by the turning of the rod associated with the throttle lever of the Ford type of automobile.

To the attainment of the above broadly stated objects and others which will present themselves as the nature of the invention is better understood, the improvement resides in the construction, combination and operative association of parts, a satisfactory embodiment of which is disclosed by the accompanying drawings.

In the drawings:

Figure 1 is a view, partly in elevation and partly in section of the engine and dash of a Ford type of automobile to illustrate the application of our improvement.

Figure 2 is a top plan view thereof.

Figure 3 is a sectional view on the line 3—3 of Figure 2.

Figure 4 is a sectional view on the line 4—4 of Figure 2.

The throttle actuating rod for the hand lever of the Ford type of automobile is indicated in Figure 1 of the drawings by the numeral 1, the engine block by the numeral 2', and the carbureter and intake manifold by the numeral 3. As the hot plate vaporizer is of the usual construction a detail description thereof will not be attempted but the lever to which the shaft is pivoted is indicated by the numeral 4. Pivotally secured to the lever 4 there is a hand operated rod 5. The rod has an arched portion at its connection with the lever 4 and is extended a suitable distance above the engine block 2'.

The rod has arranged thereon a slidable sleeve 6 and this sleeve has a rod extension provided with an offset end which is pivotally secured to a lever 7 connected to the throttle operating rod 1. Passing through the rod 5 and contacting with what we will term the inner end of the sleeve 6 there is a pin or other stop element 8.

In carrying out our invention we remove the front bolt between the head and engine block on the left hand side of the engine, but again replace the same to secure on the engine head a substantially L-shaped bracket

9. Passing through the outer end of the horizontal arm of the bracket which projects beyond the side of the engine block there is a pivot 11. This pivot has both of its ends headed, as clearly disclosed by Figure 4 of the drawings; and journaled on the pivots there is a sleeve 12 which has integrally formed on its lower end an outstanding bar or plate 13. The bar or plate 13 merges into a downwardly extending portion 14 that in turn merges into an offset end 15 and passing freely through the end 15 there is the offset end of the inner portion 16 of the lever for the foot pedal 17. The offset end 18 of the rod 16 is secured to the angle end 15 of the substantially L-shaped plate 14 by a cotter pin 19. The rod 16 is centrally bent upon itself and the portion thereof to which the pedal 17 is connected is curved and passes through a guide sleeve 20 in the floor board of the automobile. The sleeve 12 has on its upper end an arm 21 that extends rearwardly with respect to the ending block, and swivelly but removably secured to the outer end of the arm 21 there is a block 22. The rod 5 passes through a central opening in the revoluble block 22 and the said rod 5 has passed therethrough at opposite sides of the block 22 cotter pins or like stop elements 80

85

23. Surrounding the sleeve 12 there is the coil spring 24 of a spring. One arm 25 of the spring is anchored in the upstanding end of the L-shaped bracket 9, the second arm 26 of the said spring being anchored in a 90

notch in the substantially L-shaped member 14.

From the foregoing description when taken in connection with the accompanying drawings, it will be apparent that the throttle operating rod may be swung to bring the sleeve 6 against the stop element 8 to impart a longitudinal movement to the rod 5 to swing the lever 4 to operate the hot plate which, in the construction as shown will influence the angle arms on the sleeve 12, and consequently the rod 16 and the foot pedal 17 associated therewith but by removing one of the cotter pins or stop elements 23, the rod 5 can freely move through the block 22 100 without influencing these elements. By removing the said cotter pins or stop elements and arranging a small push spring in front of the cotter pin or stop element 8, as indicated by the dotted lines in Figure 1, 105 the hand throttle may be operated without moving the foot pedal. Also if desired, in

lieu of the spring construction between the sleeve, the bracket and angle member, a spring may be attached directly to the arm 21 and fixed to a suitable support on the 5 engine block. A pressure on the foot pedal will swing the angle arms and the sleeve to move the rod 5 and operate the lever 4 of the hot plate or vaporizer. Either this 10 spring or the spring 24 will return the pedal members to initial position, and it is thought that the foregoing description, when taken in connection with the drawings, will fully set forth the advantages of our construction and the simplicity thereof, to those skilled 15 in the art to which such invention relates, but it is to be understood that we do not wish to be limited to the precise details of construction herein set forth and hold ourselves entitled to such changes therefrom as fairly 20 fall within the scope of what we claim.

Having described the invention, we claim:

1. The combination with an automobile engine having a lever operated vaporizing 25 device between the carbureter and the intake manifold thereof and a lever operated rod for controlling the throttle valve of the carbureter and for actuating the lever device, of pedal operating means for also actuating the lever of the vaporizing device, including a rod connected to the lever, a sleeve arranged for slidable movement on the rod, a lever on the throttle operating rod loosely connected with the sleeve, a contact on the 30 rod for limiting the movement of the sleeve in one direction, a spring influenced pivotally supported member having offset ends, a pedal having a rod loosely connected to one of said ends, a revolute supporting block 35

on the second end of the member and 40 through which the first mentioned rod passes, and stop elements on the rod to the opposite sides of the block.

2. The combination of an automobile engine having a lever operated vaporizing device, and a hand operated rod for controlling the throttle valve of the carbureter, and for actuating the vaporizing device, of pedal means for also operating the lever of the vaporizing device, all of said means including a rod connected to the lever of the vaporizing device, a sleeve slidable on the rod and an arm extending from the sleeve, a lever fixed on the throttle operating rod and loosely connected with the sleeve rod, a removable pin passing through the first mentioned rod for limiting the sliding of the sleeve thereon in one direction, an angle bracket fixed to the engine head by one of the attaching bolts therefor, a sleeve pivotally supported on the horizontal arm of the bracket therefor, oppositely directed angle extensions at the ends thereof, spring means between the sleeve, bracket and said angle member for holding the angle member in 65 one position on the bracket, a foot pedal having a rod which is loosely and removably connected to the lower arm of the angle member, a block pivotally supported on the upper arm of the angle member and 70 through which the first mentioned rod passes and removable pins passing through the rod and arranged at the opposite sides of the block.

In testimony whereof we affix our signatures.

WILLIAM V. PENNINGTON.
PAUL C. ISOM.
